UNITED STATES PATENT OFFICE.

PIERRE C. CHAMBELLAN, OF WEST HOBOKEN, NEW JERSEY, ASSIGNOR TO THE BIGELOW CARPET COMPANY, OF NEW YORK, N. Y.

DESIGN FOR CARPET.

SPECIFICATION forming part of Design No. 23,715, dated October 23, 1894.

Application filed September 25, 1894. Serial No. 524,118. Term of patent 8½ years.

To all whom it may concern:

Be it known that I, PIERRE C. CHAMBELLAN, a citizen of the United States, residing at West Hoboken, in the county of Hudson and State of New Jersey, United States of America, have invented and produced a new and original Design for Carpets, of which the following is a specification, reference being had to the accompanying drawing, forming a part thereof, in which is represented a face view of a carpet in which the new design is embodied.

The invention relates to a design to be worked into or upon surfaces such as carpets or similar fabrics, and it consists in the novel configuration of the figures therein, as herein shown and claimed.

The design consists of the body A and the border B. The body A is decorated with bouquets representing a grouping of flowers of the rose, dahlia and lilac type, together with foliage, and the border B is correspondingly decorated, and is also ornamented with a shaded sub-border.

I claim—

1. In a design for a carpet, the body A, substantially as shown.
2. In a design for a carpet, the border B, substantially as shown.
3. The design for carpets, consisting of the body A and border B, substantially as shown.

PIERRE C. CHAMBELLAN.
